UNITED STATES PATENT OFFICE.

ISAAC BARTLEY, OF CARLISLE, ARKANSAS.

COTTON-PLANTER.

SPECIFICATION forming part of Letters Patent No. 441,349, dated November 25, 1890.

Application filed June 13, 1890. Serial No. 355,388. (No model.)

To all whom it may concern:

Be it known that I, ISAAC BARTLEY, a citizen of the United States, residing at Carlisle, in the county of Prairie and State of Arkansas, 5 have invented certain new and useful Improvements in Cotton-Planters; and I do declare the following to be a full, clear, and exact description of the invention, such as will enable others skilled in the art to which it applies to make and use the same.

My invention has relation to improvements in cotton-seeders; and it consists in the construction, novel combination, and adaptation of devices hereinafter described and claimed.

15 In the accompanying drawings, Figure 1 is a top plan view of my improved cotton-seed planter. Fig. 2 is a side elevation of the same, with the hoppers and their component parts shifted up out of an operative position. Fig. 20 3 is a side elevation of the machine with the hoppers and component parts, which are illustrated in vertical section in an operative position.

25 In the practice of my invention I do not desire to limit myself to the exact construction of the several elements illustrated, nor to any particular material in the manufacture thereof, as it is obvious that such modifications may be made therein, as fairly fall 30 within the scope of my invention.

Referring by letter to the said drawings, A indicates the main frame of my improved machine, which is composed of two transverse and two longitudinal bars so arranged 35 and connected as to form an open rectangular frame for the support of the operating elements hereinafter described.

B B designate longitudinal brace-bars connected at the sides of the frame to the front 40 and rear transverse bars thereof.

The wheel-axle C, which is suitably journaled on the lower side of the respective longitudinal bars A, carries at its ends the traveling-wheels D, which are provided with a 45 broad tread or tire, as illustrated, to enable them to serve as rollers in pressing the earth over the seed deposited by the hoppers, with which they are in line.

At a point preferably midway of the length 50 of axle C, which turns with the traveling-wheels, I fix thereon a grooved pulley E, which is adapted to receive a belt to transmit mo-

tion to the feed mechanism of the hoppers, as will be hereinafter described.

F indicates a transverse bar journaled in 55 the longitudinal bars A at a point in front of the axle C, and extending laterally on each side of the frame. This bar F, which is adapted to be rocked, has fixed on its laterally-extended branches the frames of the respective 60 hoppers, which also carry the furrow opening and the covering plows to be described.

The respective hopper-frames consist of two longitudinal strips G, which confine between them at their forward and rear ends 65 two upright blocks H, which depend from the longitudinal bars a sufficient distance and are designed to carry the furrow-openers and covering-plows. The transverse bar F, which supports the hopper-frames, takes through 70 the longitudinal bars and the intermediate rear upright blocks thereof, in which it is fixed in any approved manner.

I indicates the hoppers, which are seated in and secured to their respective frames in any 75 preferable manner. These hoppers I, which may be of the ordinary or any approved construction, and which are provided with the ordinary depending seed-conveying tubes, have suitably journaled on the top of their 80 inside walls the transverse rotatable bar J, which has its ends cranked, as illustrated at a, to operate the force-feed devices, which I will now proceed to describe.

K indicates the depending agitator-arms, 85 which are loosely journaled on the cranked ends of the rotatable bar J, and which extend down and through the mouth of the hopper to promote the feed of the seed therefrom, when the bar J is rotated. The depending 90 agitating-arms K are provided in their sides at suitable points in their length with laterally-extending pins l to assist in the agitation of the seed.

Fixed on the bar J at a point in line with 95 the axle-pulley E is a grooved pulley L, which is connected by a suitable belt with and is operated by said pulley E when the machine is in operation.

Fixed on the front side of the respective 100 forward depending blocks H is a pointed furrow-opener M, and fixed on both sides of the respective rear depending blocks H are covering-plows N. These covering-plows N, which

are inwardly disposed, are provided with slots *c* of a sufficient length, as shown, through which takes a binding-screw *d*, by which the said plows are rendered vertically adjustable.

5 O indicates a transverse beam, which extends across the forward end of the main frame and is connected to the respective hopper-frames in any approved manner.

P indicates an upright standard, which is 10 secured to and rises from the forward transverse bar A, and is designed to afford a bearing for a lever Q, which is fulcrumed thereon. This lever, which extends back to within convenient reach of the driver's seat R, has its 15 weight end of a length to extend forward beneath transverse bar O, through the medium of which it is adapted to lift the hopper and its component parts out of an operative position, and to loosen the belt connecting the 20 pulleys E and L.

It is believed that a detailed description of the operation and advantages is rendered unnecessary by the preceding specification, in which they are made obvious.

25 Having described my invention, what I claim is—

The cotton-seed planter described, compris-

ing the main frame mounted on supporting-wheels, a drive-pulley on the axle of said wheels, a shaft journaled transversely in the 30 forward portion of the main frame, hopper-frames journaled at their rear portions on the laterally-projected ends of said shaft, a cross-bar connecting said hopper-frames and adapted to rest upon the upper side of the main 35 frame so as to limit the downward movement of said hopper-frames, the furrow opening and covering shovels also secured to the hopper-frames in front and rear of the seed-discharge, the hoppers, the rotatable seed-shaft carrying 40 a pulley and connected by a belt with the pulley on the drive-shaft and having a crank at each end, the agitators depending in the hoppers from said cranked ends, and the lever pivoted in the main frame and extending 45 beneath the cross-bar connecting the hopper-frames so as to raise and lower the latter, substantially as specified.

In testimony whereof I affix my signature in presence of two witnesses.

ISAAC BARTLEY.
